UNITED STATES PATENT OFFICE

2,491,421
APPARATUS FOR PROCESSING PACKAGED
PRODUCTSHorace L. Smith, Jr., Richmond, Va., assignor to
Chain Belt Company, Milwaukee, Wis., a cor-
poration of Wisconsin

Application October 1, 1945, Serial No. 619,636

7 Claims. (Cl. 99—364)

1

The invention relates to apparatus for processing packaged products, and more especially to machines for heating and/or cooling materials, such as for example as foods, contained in sealed cans or similar containers. Prior U. S. Patent No. 2,348,440 granted May 9, 1944, on an application filed by Horace L. Smith, Jr., and Weld E. Conley, Jr., discloses a machine of this general character, and for purposes of disclosure the present invention has been illustrated and will be described as applied to such a machine, although as will appear more fully below, the invention is in no wise dependent upon many of the specific features of that machine.

Briefly, the apparatus of the aforesaid patent comprises among other things a series of power driven can-supporting rolls disposed within a tank or vat in spaced parallel relationship to provide valleys between adjacent rolls, and partly or wholly submerged in a flowing heat exchange medium such as water. Appropriately timed feeding mechanism supplies a batch of longitudinally aligned sealed cans containing the material to be processed to the valley between the first and second rolls of the series, where they are rotated by such rolls while being subjected to the heating or cooling action of the heat exchange medium. After a determined interval the batch is transferred from the first valley to the next adjacent one, and substantially simultaneously therewith a fresh batch is supplied to the first valley by the feeding mechanism. This cycle is repeated continuously, and when the cans reach the last valley they are transferred to a conveyor or other suitable discharge device with the temperature of their contents raised or lowered to the desired degree.

The present invention relates more particularly to the means for transferring the containers from valley to valley, and has for its principal object the provision of an improved mechanism which will not only effect such transfer, but which is also adapted to direct the flowing heat exchange medium against the surfaces of the rotating cans, whereby the efficiency of the heat transfer will be materially increased.

With this and other objects in view which will appear as the description proceeds, the invention resides in the novel details of construction and in the novel combinations and arrangements of parts, more fully hereinafter disclosed and particularly pointed out in the appended claims.

In the accompanying drawings forming a part of this specification:

Figure 1 is a fragmentary plan view of the feed

2

end of a processing machine of the character disclosed in the said prior Patent No. 2,348,440, equipped with one form of can transfer mechanism constructed and arranged in accordance with the invention;

Fig. 2 is an enlarged partial cross sectional view, on approximately the plane indicated by the line 2—2 of Fig. 1, looking in the direction of the arrows;

Fig. 3 is a fragmentary side elevational view, partly in section on various planes, looking from the left of Fig. 2, the parts being shown in the positions occupied between the transfer operations;

Fig. 4 is a view similar to Fig. 3, showing the positions assumed by the parts in the course of the transfer; and

Fig. 5 is a plan view of a portion of the parts shown in Fig. 3, the view being partly broken away and in section.

While as disclosed in the above mentioned patent, the machines may be constructed with a plurality of superposed tanks, or decks, of which one may be used for heating and the other for cooling, or if necessary or desired, both may be employed for either heating or cooling, the transfer mechanism is the same in each instance, and the present description will be confined to a single deck.

The can-supporting rolls 10 are disposed in horizontal parallel spaced relation in the vat or tank 11, with their axes extending transversely thereof, and with their shafts or trunnions 12 journalled in self-aligning bearings 13. Power from any appropriate source (not shown) is supplied to one of the trunnions of, for example, the third roll of the series, by a chain and sprocket drive 14, and at one side of the tank the trunnions of the odd numbered rolls of the series are interconnected by chain and sprocket drives 15, whereby such rolls may be simultaneously rotated in the same direction. The even numbered rolls of the series are driven in like manner by similar drives located at the opposite side of the tank.

The cans are introduced into the tank ahead of the first roll in end-to-end aligned relationship, by a feeding conveyor 16, which has associated with it a can gripping mechanism 17 which is intermittently operable in timed relation to the other functions of the machine to stop the line of cans on the conveyor when a predetermined number of cans has been advanced to position for transfer to the rolls 10. Such transfer from the conveyor 16 to the valley between the first and second rolls of the series is then effected by a reciprocatable feed bar 18 which is advanced and retracted

simultaneously with the operation of the members which effect transfer of the lines of cans from valley to valley of the roll series. The tank is provided adjacent its respective ends with inlet and outlet connections (of which one of the latter is indicated at 19) through which water or like heat exchange medium may be introduced and discharged, the flow being in a direction opposite to that in which the cans are advanced from valley to valley. If the machine is to function as a heater, steam coils or equivalent heating devices are disposed in the tank for submergence in the liquid heat exchange medium.

In addition to journaling the roll trunnions 12, each bearing sleeve 13 also journals a transfer arm 20, which arms extend angularly upward. The several arms at each side of the machine are all pivotally connected at their upper ends to a longitudinally extending draw bar 21, which bars are intermittently reciprocated by power mechanism, not here shown. The feed bar 18 also preferably has connections 22 (Fig. 1) with the said draw bars 21, whereby the feed bar may be actuated simultaneously with the transfer members about to be described.

The transfer arms 20 are here shown as of a bifurcated construction, and the inner hub portion 23 of each arm is provided with an arcuate extension 24 of approximately 90° in extent which, as will be especially clear from Figs. 2 and 5, is angularly disposed or offset laterally inward whereby to partially surround the end portion of its associated roll 10. The peripheral faces of these extensions are substantially concentric with the peripheries of the rolls, and to these faces of each transverse pair of arm extensions there is secured, as by screws 25, a transfer member 26 or bar of arcuate cross section. As will be clear from Fig. 3, in the normal position of the parts the upper edges of the members 26 are disposed just below the peripheral surfaces of the lines of cans occupying the valleys of the roll series; but when the transfer mechanism is operated to reciprocate the draw bars 21 and thereby oscillate the arms 20, as the latter swing in a clockwise direction (as viewed in said figure) these upper edges of the transfer bars will engage the cans to lift and shift them over the rolls, into the next valley.

This transfer action is substantially the same as that in the said prior patent, but it will be noted that in this instance the transfer bars 26 are substantially spaced from the roll peripheries, thus providing arcuate channels 27 opening directly below the lines of cans, through which the flowing heat exchange medium may freely pass to such can surfaces. It will also be noted that the extensions 24 close the sides of the passages 27. Since in the normal (Fig. 3) position the lower portions of the arcuate transfer bars 26 just clear the tank bottom, the said bars in effect act as baffles to the flowing medium, causing it to take the tortuous course indicated by the arrows 28, passing around the rolls and upwardly through the channels 27 from which it impinges directly against the peripheral surfaces of the cans 29. This appreciably increases the rate of heat exchange between the medium and the can contents, and the side members or arm extensions 24 have been found to further raise the efficiency of the apparatus by preventing escape or short-circuiting of the medium around the ends of the rolls.

A guide rail 30, supported by brackets 31, is provided adjacent each end of the rolls for pre-

venting endwise movement of the lines of cans in the valleys and during transfer from valley to valley.

What is claimed is:

- 5 1. In heat exchange apparatus for processing materials in sealed containers, a tank for containing a flowing heat exchange medium; a plurality of spaced parallel rolls mounted in said tank, providing valleys between adjacent rolls for the reception of the containers; means for transferring the containers from valley to valley, comprising a transfer bar disposed in parallel substantially spaced relation to each roll to provide a free passage for the heat exchange medium between the two, said passages opening into the respective valleys and said bars being formed and disposed to deflect the flowing medium through the passages and against the surfaces of containers disposed in such valleys; and means for moving the transfer bars into and out of the valleys to effect progressive transfer of the containers from valley to valley.
  - 10 2. In heat exchange apparatus for processing materials in sealed containers, a tank for containing a flowing heat exchange medium; a plurality of spaced parallel rolls mounted in said tank for supporting the containers in the valleys between adjacent rolls; means for transferring the containers from valley to valley, comprising a transfer bar of curved cross section partially surrounding and substantially paralleling the periphery of each roll throughout its length in completely spaced relation thereto and providing an unobstructed passage for the heat exchange medium,
  - 15 30 35 40 45 50 55 60 65 70 75
  - 20 25 30 35 40 45 50 55 60 65 70 75
  - 25 30 35 40 45 50 55 60 65 70 75
  - 30 35 40 45 50 55 60 65 70 75
  - 35 40 45 50 55 60 65 70 75
  - 40 45 50 55 60 65 70 75
  - 45 50 55 60 65 70 75
  - 50 55 60 65 70 75
  - 55 60 65 70 75
  - 60 65 70 75
  - 65 70 75
  - 70 75
2. In heat exchange apparatus for processing materials in sealed containers, a tank for containing a flowing heat exchange medium; a plurality of spaced parallel rolls mounted in said tank for supporting the containers in the valleys between adjacent rolls; means for transferring the containers from valley to valley, comprising a transfer bar of curved cross section partially surrounding and substantially paralleling the periphery of each roll throughout its length in completely spaced relation thereto and providing an unobstructed passage for the heat exchange medium, said passages opening into the respective valleys whereby the flowing medium may be directed against the surfaces of containers disposed in such valleys; and means for oscillating the transfer bars into and out of the valleys to effect progressive transfer of the containers from valley to valley.
3. In heat exchange apparatus for processing materials in sealed containers, a tank for containing a flowing heat exchange medium; a plurality of spaced parallel rolls mounted in said tank for supporting the containers in the valleys between adjacent rolls, the peripheries of said rolls being spaced from the bottom of the tank whereby the medium may flow under them; means for transferring the containers from valley to valley, comprising a transfer bar paralleling each roll in spaced relation thereto whereby to provide a free passage between the two, said bars extending upwardly from proximity to the tank bottom toward the valleys between adjacent rolls whereby they may baffle the medium flowing beneath the rolls and direct it through said passages and against the surfaces of containers disposed in said valleys; and means for moving the transfer bars into and out of the valleys to effect progressive transfer of the containers from valley to valley.
4. In heat exchange apparatus for processing materials in sealed containers, a tank for containing a flowing heat exchange medium; a plurality of spaced parallel rolls mounted in said tank for supporting the containers in the valleys between adjacent rolls, the peripheries of said rolls being spaced from the bottom of the tank whereby the medium may flow beneath them; means for transferring the containers from valley to valley comprising a transfer bar of substantially arcuate cross section partially surrounding each roll throughout its length in completely spaced relation to the periphery of such roll, said

bars extending from the tank bottom upwardly toward the valleys between adjacent rolls whereby they may baffle the medium flowing beneath the rolls and direct it into the valleys against the surfaces of containers disposed therein; and means for oscillating the transfer bars into and out of the valleys to effect progressive transfer of the containers from valley to valley.

5. A transfer element for heat exchange apparatus having a can-supporting roll, comprising a pair of spaced arms mountable for oscillation relative to such roll; and a transfer bar carried by said arms for disposition substantially parallel to the axis of the roll and in substantial completely spaced relation to the periphery thereof, whereby to provide a channel between the two for free passage of a heat exchange medium and said bar being shaped to deflect said medium through said channel.

6. A transfer element for heat exchange apparatus having a can-supporting roll, comprising a pair of spaced arms mountable for oscillation about the axis of such roll; and a transfer bar of curved cross section carried by said arms for disposition in concentric substantial spaced relation to the periphery of the roll, whereby to provide

a channel for free passage of a heat exchange medium.

7. A transfer element for heat exchange apparatus having a can-supporting roll, comprising a pair of spaced arms mountable adjacent the ends of such roll for oscillation about its axis, said arms each having an arcuate extension; and a transfer bar of arcuate cross section carried by said extensions for disposition in substantial spaced relation to the periphery of the roll, whereby to provide a channel between the two for conducting a heat exchange medium to the surfaces of cans supported by the roll.
